UNITED STATES PATENT OFFICE

101,263

DESIGN FOR A MASSAGE APPLIANCE HEAD

Dolletta M. Ackerman, Los Angeles, Calif.

Application September 3, 1935, Serial No. 58,415

Term of patent 14 years

To all whom it may concern:

Be it known that I, Dolletta M. Ackerman, a citizen of the United States, residing at Los Angeles, in the county of Los Angeles, State of California, have invented a new, original, and ornamental Design for Massage Appliance Heads of which the following is a specification, reference being had to the accompanying drawing, forming part thereof.

I claim:

The ornamental design for a massage appliance head, as shown.

DOLLETTA M. ACKERMAN.
